(57) **CLAIM**

The ornamental design for a torque wrench for a surgical device as shown and described.

DESCRIPTION

FIG. 1 is a top perspective, front, right side view of a torque wrench for a surgical device;

FIG. 2 is a bottom perspective, front, right side view of the torque wrench for a surgical device;

FIG. 3 is a top perspective, front, left side view of the torque wrench for a surgical device;

FIG. 4 is a bottom perspective, front, left side view of the torque wrench for a surgical device;

FIG. 5 is a top perspective, rear, right side view of the torque wrench for a surgical device;

FIG. 6 is a bottom perspective, rear, right side view of the torque wrench for a surgical device;

FIG. 7 is a bottom perspective, front view of the torque wrench for a surgical device;

FIG. 8 is a top view of the torque wrench for a surgical device;

FIG. 9 is a front view of the torque wrench for a surgical device;

FIG. 10 is a rear view of the torque wrench for a surgical device;

FIG. 11 is a bottom view of the torque wrench for a surgical device;

FIG. 12 is a right side view of the torque wrench for a surgical device; and,

FIG. 13 is a left side view of the torque wrench for a surgical device.

The broken lines are included for the purpose of illustrating environmental structure and form no part of the claimed design.
